UNITED STATES PATENT OFFICE

127,398

DESIGN FOR A FLUORESCENT LIGHTING FIXTURE

James E. Jordan, Aliquippa, Pa., assignor to The
Phoenix Glass Company, Monaca, Pa., a cor-
poration of West Virginia

Application October 4, 1940, Serial No. 95,639

Term of patent 14 years

To all whom it may concern:

Be it known that I, James E. Jordan, citizen
of the United States and resident of Aliquippa,
Beaver County, in the State of Pennsylvania,
have invented a new, original, and ornamental
Design for a Fluorescent Lighting Fixture, of
which the following is a specification, reference
being had to the accompanying drawing, forming
a part thereof.

In the drawing:

Figure 1 is a view in perspective of the fluo-

rescent lighting fixture showing my new design.

Figure 2 is a cross-sectional view taken upon
the line 2—2 of Fig. 1.

The end of the fixture not shown is the same
as the end shown. The broken lines across the
upper ends of the supports shown in both Figs.
1 and 2 indicate indeterminate length.

I claim:

The ornamental design for a fluorescent light-
ing fixture, substantially as shown and described.

JAMES E. JORDAN.
